United States Patent Office.

DAVID WILLIAM DE FOREST, OF BROOKLYN, NEW YORK.

Letters Patent No. 77,008, dated April 21, 1868.

IMPROVED MUCILAGE-BOTTLE.

The Schedule referred to in these Letters Patent and making part of the same.

TO ALL WHOM IT MAY CONCERN:

Be it known that I, DAVID WILLIAM DE FOREST, of the city of Brooklyn, in the county of Kings, and State of New York, have invented a new and useful Improvement in Mucilage-Bottles; and I do hereby declare that the following is a full, clear, and exact description of the construction and operation of the same, reference being had to the accompanying drawings, in which—

The figure represents a side elevation thereof.

The nature of my invention consists in making the mouth of a mucilage-bottle flaring or bell-shaped, so as to receive the brush without the liability of the mucilage gathering on or around the mouth, the lower part of the neck being made straight, to receive and hold the cork, and a bulge or swell made below the neck, of such size and shape as to form a shoulder, against which to press the superfluous mucilage from the brush, and thus preventing the liability of daubing the mouth of the bottle.

To enable others skilled in the art to make and use my invention, I will proceed to describe its construction and operation.

I make the bottle, A, with a bell-shaped mouth and neck B, the lower part of the neck C being made straight, and a bulge, D, below the neck, the bulge or swell being of such size and shape as to form nearly a square shoulder with the lower part of the neck.

The mouth and neck of mucilage-bottles now in use being straight, the brush is liable to catch over the top in being inserted in the bottle, and, in being removed, must be pressed against the side of the neck to remove the superfluous mucilage, and thus the mouth and neck become daubed inside and outside, rendering the use disagreeable and difficult.

I have avoided these difficulties by making the mouth bell-shaped, as described, so that the brush may be readily inserted, without the liability of catching over the top of the bottle, and the flaring shape of the mouth allows the brush to be brought properly against the shoulder, thus removing from the brush the superfluous mucilage, which falls back into the bottle, and thus the waste and inconvenience of the accumulation of the gum upon the mouth and neck of the bottle are prevented.

Having thus fully described my invention, what I claim therein as new, and desire to secure by Letters Patent, is—

The shape of the mouth and neck of the bottle, in combination with the bulge forming the shoulder, substantially in the manner and for the purposes as herein described.
